Attorney R. W. M. Kelly

United States Patent Office.

AMOS S. KELLY, OF HAVERHILL, MASSACHUSETTS.

Letters Patent No. 95,805, dated October 12, 1869.

IMPROVEMENT IN SHOES.

The Schedule referred to in these Letters Patent and making part of the same.

To all persons to whom these presents may come:

Be it known that I, AMOS S. KELLY, of Haverhill, of the county of Essex, and State of Massachusetts, have invented a new and useful Invention, having reference to Shoes; and do hereby declare the same to be fully described in the accompanying drawings, of which—

Figure 1 is a top view, and

Figure 2, a side elevation of a shoe provided with my invention.

Figure 3 is a top view of the vamp, as slit, preparatory to being bent at the instep, or opened for the reception of the gores.

In carrying out my invention, I slit the vamp A on both flanks, from points at or near the middle of the base of the instep backward to the opposite edges of the vamp, in manner as shown at *a a* in fig. 3.

Next I bend up the instep-part or back portion *b* of the vamp into an obtuse angle with the front portion *d*, so as to draw the two edges of each of the slits apart from each other the necessary distance to cause the instep-part of the vamp, when the shoe is made, not to uncomfortably bind on the instep of the wearer of the shoe.

Next I insert and fix, by sewing or otherwise, in

each of the slits, when so opened, a gore, *c*, to fill the space.

The shoe is next to be finished in the ordinary way.

In this manner I am enabled to make not only an ornamental shoe, but one which usually will fit better to the instep, and not bind inconveniently thereon, as would be the case often were the vamp not cut and bent as explained.

My invention is specially applicable to slippers, in which I usually make the gore of pieces of red woven leather, and the vamp of black glazed leather, or that of other proper kind or color.

In the drawings—

B denotes the heel-piece, or that part of the shoe-upper which is back of the vamp.

The sole is shown at *C*.

I claim the new or improved manufacture of shoe, as made with the slits and gores arranged on the vamp, and with the instep-part of the vamp bent to an angle with the front portion of the said vamp, in manner as and for the purpose specified.

AMOS S. KELLY.
